UNITED STATES PATENT OFFICE

ALBERT T. LINNEY, OF LEXINGTON, KENTUCKY

TOY PISTOL

Application filed February 18, 1930. Serial No. 429,390.

This invention relates to toys and more particularly to a toy pistol which will not only afford amusement to children but may also be used as an advertising medium by 5 merchants. One object of the invention is to provide a toy pistol including a body portion, formed of stiff cardboard and of such shape that it may be easily held in one hand while swinging motion is imparted thereto 10 by rapidly moving the arm and cause a cracker formed of thin paper to be expelled from between the leaves of the body.

Another object of the invention is to provide a toy of this character in which the leaves 15 of the cardboard body will be hingedly connected in a very effective manner along their inner or upper edges and the leaves prevented from easily becoming detached or torn from each other when the toy is in use.

Another object of the invention is to permit the body portion of the toy to be formed 20 from a unitary blank of cardboard.

The invention is illustrated in the accompanying drawing wherein,

Figure 1 is a view showing the improved 25 toy in side elevation,

Figure 2 is a sectional view taken through the handle portion of the toy along the line 2—2 of Figure 1,

Figure 3 is a sectional view taken along the 30 line 3—3 of Figure 1, and

Figure 4 is a view of the blank from which the body portion is formed, one corner portion of the blank being broken away.

This toy pistol consists of a body portion 35 adapted to be held in one hand and having stiff leaves to the forward ends of which is attached a cracker consisting of a sheet of thin paper adapted to be folded and tucked between the leaves. By holding the rear portion of the body in one hand and swinging the arm the sheet of thin paper constituting the cracker will be forced outwardly and cause a loud noise closely resembling the discharge of a pistol. Therefore, the toy will 40 be amusing to children and since the body portion is formed of cardboard upon which advertising matter may be printed it will serve very effectively as an advertising medium.

The body portion of this toy is formed from a cardboard blank shown in Figure 4 and indicated in general by the numeral 1. This blank consists of a substantially oblong sheet of stiff cardboard having side portions or sections 2 and 3 to form leaves for the body and the forward end portions of the side sections are integrally united while rearwardly of the united forward end portions the two sections are separate from each other. A line of scoring 4 is provided so that the blank may be 50 easily folded. The rear portion of each side section or leaf has its margin cut to define a handle 5 representing the grip or butt of a pistol and slightly in front of the handle the leaf has an opening 6 formed therein to receive a finger of a person holding the toy. Tongues or flaps 7 and 8 are formed along the inner edge portion of the section 2 by cutting this section of the blank as shown 55 at 9 and from the inner end of the cut 9 the section 2 is scored along the dotted lines 10 and 11 so that the tongues or flaps 7 and 8 may be folded downwardly. An opening 12 is formed through the flap 11 intermediate 60 at 9 and from the inner end of the cut 9 the section 2 is scored along the dotted lines 10 and 11 so that the tongues or flaps 7 and 8 may be folded downwardly. An opening 12 is formed through the flap 11 intermediate 65 at 9 and from the inner end of the cut 9 the section 2 is scored along the dotted lines 10 and 11 so that the tongues or flaps 7 and 8 may be folded downwardly. An opening 12 is formed through the flap 11 intermediate 70 at 9 and from the inner end of the cut 9 the section 2 is scored along the dotted lines 10 and 11 so that the tongues or flaps 7 and 8 may be folded downwardly. An opening 12 is formed through the flap 11 intermediate 75 at 9 and from the inner end of the cut 9 the section 2 is scored along the dotted lines 10 and 11 so that the tongues or flaps 7 and 8 may be folded downwardly. An opening 12 is formed through the flap 11 intermediate 80 at 9 and from the inner end of the cut 9 the section 2 is scored along the dotted lines 10 and 11 so that the tongues or flaps 7 and 8 may be folded downwardly. An opening 12 is formed through the flap 11 intermediate 85 at 9 and from the inner end of the cut 9 the section 2 is scored along the dotted lines 10 and 11 so that the tongues or flaps 7 and 8 may be folded downwardly. An opening 12 is formed through the flap 11 intermediate 90 at 9 and from the inner end of the cut 9 the section 2 is scored along the dotted lines 10 and 11 so that the tongues or flaps 7 and 8 may be folded downwardly. An opening 12 is formed through the flap 11 intermediate 95 at 9 and from the inner end of the cut 9 the section 2 is scored along the dotted lines 10 and 11 so that the tongues or flaps 7 and 8 may be folded downwardly.

After the blank has been cut from a sheet of cardboard it is folded along the line 4 and the tongues or flaps 7 and 8 folded along the lines 10 and 11. Glue is applied to the outer surface of the flap 8 so that it will adhere to the inner surface of the side section 3 and the inner surface of the flap 7 is similarly treated with glue so that it will adhere to the outer surface of the section 3. Therefore, the two sections or leaves will be hingedly connected and while they may be swung apart they will normally remain close to each other. Either before the blank is folded or afterward a cracker 14 consisting of a sheet of thin paper has its marginal portions at one end pasted against the forward ends of the two sections or leaves 2 and 3 and this sheet is folded longitudinally and tucked inwardly 100 between the leaves.

When the toy is in use, the handle 5 of the two leaves which represents the butt or grip of a pistol is grasped in one hand and a finger is passed through the openings. Back of the opening 6 of the leaf 2 and the opening 12 of the flap 7 the sheet of cardboard is marked to represent a trigger 16 and therefore the child using the toy is apparently holding a pistol in a natural manner with one finger engaged with the trigger. Since one finger is passed through openings formed in the two leaves, it will be possible for the child to retain the leaves in slightly spaced relation to each other and thereby prevent the leaves from binding too tightly against the folded cracker. By raising the arm and then swinging the arm forwardly and downwardly the folded sheet of paper or cracker will be caused to be expelled from between the forward ends of the leaves and create a loud noise closely resembling the discharge of a pistol.

Having thus described the invention, I claim:

1. A toy comprising a body having companion leaves, the adjoining sides of the forward portions of said leaves being united, one leaf having a flap extending from its inner side rearwardly of its connection with the other leaf, said flap being secured against the second leaf and constituting a hinge member and a reinforcement for the leaves, and a cracker consisting of a sheet secured to the forward ends of the leaves and adapted to be folded between the leaves.

2. A toy comprising companion leaves of stiff material disposed in side to side relation to each other and having adjoining side edges of their forward portions integrally united, transversely extending flaps carried by one leaf rearwardly of the united forward portions of said leaves, said flaps being folded downwardly and secured one against the outer face of a leaf and the other against the inner face of a leaf, said flaps constituting hinge members and reinforcements for the leaves, and a cracker secured to the forward ends of said leaves and adapted to be tucked between the leaves.

3. A toy comprising companion leaves of stiff material disposed in side to side relation to each other and having adjoining side edges of their forward portions integrally united, transversely extending flaps projecting from one leaf rearwardly of the united forward end portions of the leaves and disposed one in front of the other, the front flap being secured against the inner face of the second leaf and the rear flap being secured against the outer face of the second leaf, and a cracker carried by the forward ends of said leaves and adapted to be tucked between the leaves.

4. A toy comprising companion leaves of stiff material disposed in side to side relation to each other and having adjoining side edges

of their forward portions integrally united, transversely extending flaps projecting from one leaf rearwardly of the united forward end portions of the leaves and disposed one in front of the other, the front flap being secured against the inner face of the second leaf and the rear flap being secured against the outer face of the second leaf and terminating adjacent the lower edge thereof, the rear portions of said leaves being shaped to define a grip and the leaves and rear flap having registering openings formed through the same in front of the grip to receive a finger when the toy is held by the grip, and a cracker consisting of a sheet of thin material secured to the forward ends of said leaves and adapted to be folded longitudinally and tucked between the leaves.

5. A toy comprising a body having companion leaves formed with openings disposed to register when the leaves are in face to face engagement with each other and form a finger passage, a flap carried by one leaf and formed with an opening, said flap being secured against the second leaf with its opening registering with the opening therein and serving as a hinge and reinforcement for the leaves, and a cracker carried by said leaves.

6. A toy comprising a body having companion leaves formed with openings disposed to register when the leaves are in face to face engagement with each other and form a finger passage, portions of the leaves rearwardly of the openings forming a grip, a flap extending from the inner side of one leaf and adapted to be secured against the other leaf in overlapping relation thereto to form a hinge and reinforcement for the leaves, said flap having a depending portion formed with an opening registering with the opening in the leaf, and a cracker carried by said leaves.

In testimony whereof I affix my signature.
